UNITED STATES PATENT OFFICE.

JOHN SCHUMACHER, OF LOS ANGELES, CALIFORNIA.

REINFORCED PLASTER BOARD.

Application filed November 4, 1924. Serial No. 747,795.

To all whom it may concern:

Be it known that I, JOHN SCHUMACHER, a citizen of the United States, and resident of Los Angeles, in the county of Los Angeles, State of California, have invented new and useful Improvements in Reinforced Plaster Board, of which the following is a specification.

This invention relates to the general class 10 of articles known as plaster board, plaster lath and the like and hereinafter is broadly referred to as plaster board. The present invention pertains particularly to that type of board having a cementitious body of slab 15 form. Such articles during transit, installation in structures, and use thereafter are exposed to strains at the edges tending to crack, split and otherwise damage the same.

The objects of this invention are broadly 20 to provide a board having a reinforced edge which is durable, economical, and efficient; and more specifically to provide a board having an edge reinforced longitudinally, laterally, and transversely.

25 These objects together with other objects and corresponding accomplishments are obtained by means of the embodiment of my invention illustrated in the accompanying drawings, in which:

30 Fig. 1 is an edge view of a board constructed in accordance with my invention; Fig. 2 is a plan view of a fragment of the board, a portion of a covering sheet and the body being broken away to better show the 35 reinforcement member; and Fig. 3 is a perspective view of a fragment of the reinforcement member.

The article shown herein as embodying the 40 invention is a type of board in which plaster forms the body thereof and this body is enclosed on one or both opposite faces with the pliable sheets such as paper. Referring more particularly to the drawing, 5 is the plaster body and 6 and 7 are paper 45 sheets applied to opposite faces thereof and adhering thereto. The manner and means of making such a board is well known in the art. Embedded in the edges are reinforce-

ment strips preferably of paper and herein-
after more fully described.

50 Strips of paper 8 are embedded in the plaster body during manufacture. These strips are slit laterally as indicated by 9, and the slit portions bent upwardly to form an echelon file or ridges or triangular 55 tongues indicated by 10.

It will be observed by inspection of Figs. 1 and 2 that the body of the strip serves as a reinforcement longitudinally of the board. The ridges by reason of their position serve as a reinforcement of the board at the edge both transversely and laterally of the board. The construction is such as to effectively reinforce the edges in all directions. The reinforcement strip being made 60 of paper will be suitably bound to the body of the board, and being light in weight, it is both durable and does not detract from the character of the board and the edge.

65 What I claim is:

1. A plaster board of the character described comprising a cementitious body, a reinforcement strip embedded in the edge and extending longitudinally thereof, said strip having portions protruding from its 70 face transverse to the board, the planes of said portions inclining laterally of the length of the board.

2. A plaster board of the character described comprising a cementitious body, a reinforcement strip embedded in the edge and extending longitudinally thereof, said strip having ridges protruding from its face and upset therefrom and extending trans- 75 verse to said board.

3. A plaster board of the character described comprising a cementitious body, a reinforcement strip embedded in the edge and extending longitudinally thereof, said strip having ridges upset therefrom, ex- 80 tends transverse to the board and ar- ranged in echelon formation.

4. A plaster board of the character described comprising a cementitious body, a reinforcement strip of pliable material em- 85 bedded in the edge and extending longitudi-

nally thereof, said strip being slit laterally to form triangular tongues upset therefrom so as to extend transversely of the board.

5. A plaster board of the character described comprising a cementitious body a reinforcement strip of pliable material embedded in the edge thereof and extending longitudinally thereof, said strip being slit laterally to form triangular tongues upset

therefrom with their planes arranged in 10 echelon formation so as to reenforce the board longitudinally, laterally and transversely.

In witness that I claim the foregoing I have hereunto subscribed my name this 27th 15 day of October, 1924.

JOHN SCHUMACHER.
